CONTAINER

Edward F. Ganter, Utica, N. Y.

Application October 17, 1938, Serial No. 235,519

4 Claims. (Cl. 221—106)

This invention relates to containers and more particularly to a dispensing container for domestic, household or individual use in the dispensing of measured quantities of commodities such as coffee and the like which deteriorate upon exposure to the atmosphere.

The invention has for its prime object to produce a simple yet practical and efficient dispensing container which is normally sealed to protect the contents thereof against deterioration and from which a measured quantity of the contents may be withdrawn, at will, for immediate use.

A particular object is to provide in a device of this character a special revolvable measuring cup which normally seals the discharge outlet of the container and is operable by the manipulation of a drawer or the like whereby to transfer a measured quantity of the contents to the drawer.

With the foregoing and other objects and advantages to be attained, the invention consists in the general structural assembly, and in the particular parts, combinations and arrangements of parts as hereinafter described and set forth in the appended claims, reference being had to the accompanying drawing illustrating a practical adaptation of the invention and in which—

Figure 1 is a vertical longitudinal section through the device;

Figure 2 is a transverse vertical section on line 2—2 of Figure 1; and

Figure 3 is a fragmentary horizontal section taken on or about the line 3—3 of Figure 1 and showing the drawer element of the device moved to its innermost position to effect the discharging actuation of the measuring cup.

Referring now to the drawing, the numeral 10 designates the hopper bottom portion of a container for dispensing coffee either in the whole bean or ground condition, or for cereals or other commodities of a similar character. Obviously the upper portion of the container (not shown) may be of any desirable form. Preferably, as a coffee container, the body portion is generally cylindrical and provided with a filling opening at its top having an air-tight removable closure. The tapered hopper bottom portion 10, therefore, is substantially funnel shaped, as shown, and merges into a hollow spherical shell 11 with a circular opening 12 therebetween.

The spherical shell portion 11 is connected by neck 13 to the rectangular lower casing 14 which constitutes a supporting base for the device and is preferably mounted on corner lugs or supporting feet 15.

The communicating opening 16 through the

connecting neck 13 between the spherical shell portion 11 and rectangular base 14 is normally closed by a spherical cup member 17 which is fitted circumferentially to the corresponding inner face of the spherical casing portion 11 and having an opening 18 of substantially the same diameter as the opening 12 between the hopper bottom portion 10 and said spherical shell portion 11, and normally registering with said opening 12.

The spherical cup member 17 is provided with diametrically opposite trunnions 19 which are extended through bearings provided therefor in the adjacent portions of the spherical shell 11 and having gears 20 fixed on their outer ends, said trunnions, as shown, being provided by headed studs having squared portions 21 fitted in counterpart openings provided therefor in the cup member so that the studs are forced to rotate with the cup member. Meshing with the gears 20 are toothed sectors 21' which are formed on the upper ends of rocking levers 22, said levers working through slots 23 provided in the top of the rectangular base portion 14 of the device, and being pivotally mounted, as at 24, on the inner face of the adjacent wall portions below said slots 23.

The lower ends of said rocking levers 22 are pivotally attached, as at 25, to the ends of the parallel leg members 26 extending forwardly from the cross bar 27 of an operating yoke which is provided at its opposite ends with upstanding lugs 28, said lugs being connected by spring elements 29 to studs 30 projecting inwardly from the side walls of the rectangular base portion of the device. Normally, the spring elements 29 are retracted and the yoke comprising the cross bar 27 and the leg portions 26 is thereby yieldably held in a forward position with the rocking levers 22 positioned so that their upper portions, just above the pivots 24, are in contact with the rear ends of the slots 23, in which position the spherical cup member 17 is in its normal position with its opening 18 in registration with the opening 12 at the bottom of the hopper bottom of the device 10.

Slidable in the rectangular base portion 14 is a drawer element 31, said drawer element, in its normal closed position, having its front end wall 32 flush with the front end of the base portion 14 and its rear wall 33 being close to the cross bar 27 of the operating yoke for the rocking levers 22, in which position of the drawer element its rear wall 33 is also slightly rearward of the opening 16 through which communication is established between the spherical shell portion 11 and said rectangular base portion 14.

To operate the spherical cup member 17 and extract a measured quantity of the contents from the container, the drawer element 31 is moved inwardly as shown in dotted lines in Figure 1 and 5 in full lines in Figure 3, thereby moving the cross bar 27 and its integral leg extensions 26 rearwardly therewith, stretching the spring elements 29 and rocking the lever members 22 on their pivots 24 and accordingly swinging the sectors 10 21 forwardly and thereby rotating the gears 20 and, of course, the cup member 17, the ratio of the gearing being such that when the drawer element 31 has reached the limit of its inward movement the opening 18 of the cup member 15 17 is brought into registration with the opening 16 and the contents of the cup are discharged into the drawer element. In this discharge position of the cup member 17 the opening 12 of the bottom of the hopper 10 is closed, and in 20 this connection it is noted that at all times, whether the cup member 17 is in its receiving relation to the hopper 10 or in the discharging relation to the drawer element 31, the container is sealed against the deteriorating effect of the 25 outside air, not only because of the relative proportions of the surface area of the cup member 17 and the openings 12 and 16 of the device, but by reason of instant restoration of the cup member 17 to normal receiving position with 30 relation to the opening 12 in the hopper bottom 10 which occurs by the reaction of the spring elements 29 of the operating yoke and rocking levers 22 immediately during the returning movement of the drawer element 31 to its normal forward position in the base portion 14 of the device. 35

As hereinbefore described the rear end portions of the slots 23 afford stops to arrest movement of the rocking levers 22 to prevent over-travel of the cup member 17 in rotation back to its normal receiving position with relation to the hopper 10. To limit the movement of the cup member 17 in its rotation to discharge position with relation to the drawer element 31 the stud members 38 to which the spring elements 29 are attached 40 afford stops for the lower end portions of the rocking levers 22, by which provision also an effective stop is provided for the drawer element 31 at the limit of its inward movement from normal position to actuate the cup member. To 45 guide the yoke members 26 in both their rearward and forward movements in the actuation of the cup member 17 studs 34 are provided on the side walls of the rectangular base portion 14 so as to overhang said yoke portions 26 and 50 prevent undue upward swing thereof under the pull of the spring elements 29.

In order to guide the drawer element 31 in its reciprocatory movement within the base portion 14 of the device and to space its side walls 60 from the side walls of said base portion 14 to afford ample clearance for the rocking levers 22 and several cooperative actuating elements, cleats 35 are provided on the bottom of the base portion 14 so as to extend longitudinally thereof adjacent 65 the respective side walls and crosswise thereof adjacent the end wall. The drawer element rides on the bottom of the base portion 14 and between the longitudinal side cleats 35.

From the foregoing it is seen that a dispensing 70 container is produced which is specially advantageous in holding coffee and other commodities which are very susceptible to deterioration upon exposure to atmospheric conditions, it being only necessary to first move the drawer element 31 inwardly a slight distance from normal position 75

to effect the dumping of the spherical cup member 17 which latter is quickly restored to normal receiving position with relation to the hopper bottom 10 when the drawer element 31 is returned to its normal position, which return movement of the drawer element is effected automatically by the reaction of the spring elements 29 on the cross bar 27 of the operating yoke, which latter presses against the inner end of the drawer element even should the operator neglect to 10 restore the drawer element to normal position manually. Furthermore, there is a material advantage in the device of the present invention in that after the drawer element 31 is withdrawn and the contents dumped therefrom no more of 15 the contents of the container enters the drawer element until the latter is again actuated as hereinabove described.

What is claimed is:

1. In a dispensing container, a base portion 20 having a drawer element therein, the drawer element being normally positioned forwardly in the base portion but movable inwardly from such normal position within the base portion, a hopper above said base portion, said hopper and base 25 portion being connected by a spherical shell, the upper portion of the shell communicating with the hopper through a discharge opening from the hopper and the lower portion of the shell having a discharge opening in communication 30 with the base portion, a spherical cup member mounted rotatably in said spherical shell with sealing effect, operating means for said spherical cup having provision for holding the cup normally in position with its opening in receiving 35 relation to the discharge opening of the hopper, said operating means for the cup having provision whereby an initial inward movement of the drawer element from normal position in the base portion of the device effects the rotation of 40 the spherical cup to bring the opening of the cup into delivery relation to the discharge opening between the spherical shell and base portion of the device, said cup member sealing the discharge opening from the hopper during movement to, and while in, delivering position, and being automatically restored to normal position and in sealing relation to the discharge opening between the spherical shell and the base portion 45 when the drawer element is returned to its normal position in said base portion.

2. A dispensing container of the character described, comprising an upper container body having a hopper bottom and base portion provided with a removable drawer element, the 55 drawer element being normally positioned forwardly in the base portion but movable inwardly from such normal position within the base portion, a rounded connecting casing between said upper container body and base portion, said 60 connecting casing being open at its top for communication with the upper container body through the opening of the hopper bottom of said body and being open at its bottom for communication with the interior of said base portion 65 through a transfer opening provided in said base portion above the drawer element therein, a rotatable cup correspondingly rounded and fitted in said connecting casing with constant sealing 70 effect between said upper container body and said base portion but in normal receiving relation to the opening of the hopper bottom of said upper container body, operating means for rotating said cup and having provision for holding 75

the cup yieldably in its normal receiving position, the drawer, when moved inwardly from its normal position within the base portion, engaging and actuating said cup operating means and effecting the rotation of the cup from its normal receiving position to a discharge position with relation to the transfer opening of said base portion.

3. In a dispensing container, a rectangular base portion having a removable drawer element therein, a spherical shell above said portion having a discharge opening in communication with said base portion above the drawer therein, an upper container body having a funnel shaped hopper bottom communicating with the upper portion of said spherical shell, a spherical cup fitted rotatably in said spherical shell with an air sealing effect, said cup being mounted on trunnions extending through diametrically opposed bearing openings at the opposite sides of said spherical shell, gears fixed on the outer ends of said trunnions, rocking levers mounted on said base portion and having toothed sectors at their upper ends engaging said gears, the lower ends of said rocking levers extending into said base portion near the opposite sides thereof, a yoke member comprising a cross bar and parallel forwardly extending leg portions which are pivotally attached at their ends to said rocking levers, spring elements moving said yoke forward and actuating said connected rocking levers to rotate said spherical cup to normal receiving position in relation to the discharge opening of the funnel shaped hopper and for yieldingly holding the cup in such position, the inner end of the drawer in said base portion terminating forwardly of but close to said cross bar of said yoke in the normal position of the drawer, the drawer being movable inwardly from this normal position in the base portion to engage and move said yoke cross bar rearwardly and effect the rotation of the cup from its normal receiving

position with relation to the funnel shaped hopper to a position in discharging relation to the base portion of the device above the drawer element.

4. A dispensing container comprising an upper container body having a funnel shaped hopper bottom merging communicably into a spherical connecting shell, said shell merging at its bottom communicably with the upper portion of a rectangular hollow base portion, a removable drawer element in said base portion, the front end of said drawer being normally flush with the corresponding end of said base portion and the rear of said drawer element terminating short of the rear wall of the said base element, said drawer being movable to a position inwardly from its normal position, and in any position between normal and the limit of inward movement, said drawer underlying a discharge opening of said spherical connecting shell, a spherical cup fitted rotatably in said spherical connecting shell with air sealing effect, said cup being mounted on trunnions extended through diametrically opposed bearings in said shell, gears on the outer ends of said trunnions, lever members pivoted on said base portion of the device and having gear sectors engaging said ears on the cup trunnions, spring actuated operating means connected to said levers for effecting rotation of said spherical cup to normal receiving position with relation to the discharge opening of said hopper and for yieldingly holding the cup in such position, said operating means for the lever members being engaged and actuated by the inner end portion of said drawer element when the latter is moved inwardly from its normal position in the base portion of the device whereby to rotate the spherical cup into discharge relation to the communicating opening between said spherical connecting shell and said base portion of the device.
